(57) **ABSTRACT**

A new and distinct cultivar of *Osteospermum* plant named
'Balserdarp', characterized by its dark purple-colored
flowers, medium green-colored foliage-colored foliage, and
moderately vigorous and upright-mounded growth habit.

1 Drawing Sheet

1

Latin name of genus and species of plant claimed:
Osteospermum ecklonis.

Variety denomination: 'Balserdarp'.

BACKGROUND OF THE INVENTION

The present invention relates to a new and distinct cultivar
of *Osteospermum* plant botanically known as *Osteospermum*
ecklonis and hereinafter referred to by the cultivar name
'Balserdarp'.

The new cultivar originated in a controlled breeding program
in Santa Paula, Calif. during August 2005. The objective
of the breeding program was the development of
Osteospermum cultivars that are freely flowering with
unique flower coloration and a freely branching, compact,
and upright growth habit.

The new *Osteospermum* cultivar is the result of cross-
pollination. The female (seed) parent of the new cultivar is
the proprietary *Osteospermum ecklonis* breeding selection
designated 231-6op-1, not patented, characterized by its
dark reddish purple-colored flowers, medium green-colored
foliage, and moderately vigorous, upright-mounded growth
habit. The male (pollen) parent of the new cultivar is the
proprietary *Osteospermum ecklonis* breeding selection designated
285-2, not patented, characterized by its medium
purple-colored flowers, medium green-colored foliage, and
moderately vigorous, upright-mounded growth habit. The
new cultivar was discovered and selected as a single flowering
plant within the progeny of the above stated cross-
pollination during February 2006 in a controlled environment
at Santa Paula, Calif.

Asexual reproduction of the new cultivar by terminal stem
cuttings since February 2006 at Santa Paula, Calif., Arroyo
Grande, Calif.; and West Chicago, Ill. has demonstrated that
the new cultivar reproduces true to type with all of the
characteristics, as herein described, firmly fixed and retained
through successive generations of such asexual propagation.

2

SUMMARY OF THE INVENTION

The following characteristics of the new cultivar have
been repeatedly observed and can be used to distinguish
'Balserdarp' as a new and distinct cultivar of *Osteospermum*
plant:

1. Dark purple-colored flowers;
2. Medium green-colored foliage; and
3. Moderately vigorous and upright-mounded growth
habit.

Plants of the new cultivar differ from plants of the female
parent primarily in flower color and flower size. The new
cultivar has a deeper purple flower color and has smaller
flowers, as measured by flower diameter, than the female
parent. Plants of the new cultivar differ from plants of the
male parent primarily in flower color and flower size. The
new cultivar has a darker flower color and has larger flowers,
as measured by flower diameter, than the male parent.

Of the many commercially available *Osteospermum*
cultivars, the most similar in comparison to the new cultivar
is Serenity Purple 'Balserpup', U.S. Plant Pat. No. 16,477.
However, in side by side comparisons, plants of the new
cultivar differ from plants of 'Balserpup' in at least the following
characteristics:

1. Plants of the new cultivar have a ray floret color different
from plants of 'Balserpup';
2. Plants of the new cultivar are shorter than plants of
'Balserpup'; and
3. Plants of the new cultivar have a shorter peduncle
length than plants of 'Balserpup'.

BRIEF DESCRIPTION OF THE PHOTOGRAPHS

The accompanying photographs show, as nearly true as it
is reasonably possible to make the same in color illustrations
of this type, typical flower and foliage characteristics of the
new cultivar. Colors in the photographs differ slightly from
the color values cited in the detailed description, which

accurately describes the colors of 'Balserdarp'. The plants were grown in 4.5 inch pots for 12 weeks in a greenhouse at West Chicago, Ill. Plants were given one pinch at transplant.

FIG. 1 illustrates a side view of the overall growth and flowering habit of 'Balserdarp'.

FIG. 2 illustrates a close-up view of an individual inflorescence of 'Balserdarp'.

DETAILED BOTANICAL DESCRIPTION

The new cultivar has not been observed under all possible environmental conditions to date. Accordingly, it is possible that the phenotype may vary somewhat with variations in the environment, such as temperature, light intensity, and day length, without, however, any variance in genotype.

The chart used in the identification of colors described herein is The R.H.S. Colour Chart of The Royal Horticultural Society, London, England, 2001 edition, except where general color terms of ordinary significance are used. The color values were determined on Jun. 12, 2008 between 9:00 a.m. and 11:00 a.m. under natural light conditions in West Chicago, Ill.

The following descriptions and measurements describe plants produced from cuttings from stock plants and grown in a glass-covered greenhouse under conditions comparable to those used in commercial practice. The plants were grown at West Chicago, Ill. in 4.5 inch pots for 12 weeks utilizing a soilless growth medium. Plants were given one pinch at transplant. Greenhouse temperatures were maintained at approximately 70° F. to 77° F. (21° C. to 25° C.) during the day and approximately 65° F. to 68° F. (18° C. to 20° C.) during the night. Greenhouse light levels of 2,500 foot-candles to 6,000 footcandles were maintained during the day. Measurements and numerical values represent averages of typical plants.

Botanical classification: *Osteospermum ecklonis* cultivar Balserdarp.

Parentage:

Female parent.—Proprietary *Osteospermum ecklonis* breeding selection designated 231-6op-1, not patented.

Male parent.—Proprietary *Osteospermum ecklonis* breeding selection designated 285-2, not patented.

Propagation:

Type cutting.—Terminal stem.

Time to initiate roots.—Approximately 9 to 12 days.

Time to produce a rooted cutting.—Approximately 28 to 32 days.

Root description.—Fibrous.

Rooting habit.—Freely branching.

Plant description:

Commercial crop time.—Approximately 10 to 13 weeks from a rooted cutting to finish in a 10 cm pot.

Growth habit and general appearance.—Moderately vigorous and upright-mounded.

Size.—Height from soil level to top of plant plane: Approximately 25.1 cm. Width: Approximately 29.8 cm.

Branching habit.—Freely branching, pinching improves basal branching. Quantity of main branches per plant: Approximately 4.

Branch.—Strength: Strong. Length to base of peduncle: Approximately 17.4 cm. Diameter: Approximately 5.0 mm. Length of central internode: Approximately 7.4 mm. Texture: Glabrous. Color of

young stem: 144B. Color of mature stem: 144B with a faint overlay of 187A.

Foliage description:

General description.—Quantity of leaves per main branch: Approximately 17. Fragrance: Pungent. Form: Simple. Arrangement: Alternate.

Leaves.—Aspect: Acute angle to stem becoming an obtuse angle with age. Shape: Spatulate. Margin: Widely dentate. Apex: Acute becoming rounded with age. Base: Attenuate. Venation pattern: Pinnate. Length of mature leaf: Approximately 5.9 cm. Width of mature leaf: Approximately 4.0 cm. Texture of upper and lower surfaces: Densely pubescent on margin and sparsely glandular pubescent on surface. Gland color: Colorless. Color of upper surface of young foliage: 137A with venation of 145C. Color of lower surface of young foliage: 138B with venation of 144D. Color of upper surface of mature foliage: 137A with venation of 145B. Color of lower surface of mature foliage: 138A with venation of 144D.

Petiole.—Length: Approximately 1.7 cm. Diameter: Approximately 5.0 mm. Texture: Mixture of glandular and non-glandular pubescence. Gland color: Colorless. Color: 145B.

Flowering description:

Flowering habit.—'Balserdarp' is freely flowering under outdoor growing conditions with substantially continuous blooming from spring through autumn and year-round in greenhouse environment.

Lastingness of individual inflorescence on the plant.—

Approximately 8 to 10 days.

Inflorescence description:

General description.—Type: Solitary, composite. Persistent. Shape: Round. Aspect: Facing upward. Arrangement: Terminal, held above the foliage, arising from leaf axils. Disc and ray florets develop acropetally on a capitulum. Fragrance: Pungent. Quantity per plant: Approximately 12. Diameter: Approximately 7.0 cm. Depth: Approximately 1.9 cm.

Peduncle.—Strength: Strong. Aspect: Erect. Length: Approximately 7.3 cm. Diameter: Approximately 2.0 mm. Texture: Sparsely glandular pubescent. Gland color: Colorless. Color: 144B.

Bud.—Rate of opening: Generally takes 4 to 6 days for bud to progress from first color to fully open flower. Quantity per plant: Approximately 7.

Bud just before opening.—Shape: Ovoid. Length: Approximately 1.6 cm. Diameter: Approximately 1.0 cm. Color: 154B; as bud opens, an overlay of N187C develops.

Ray florets.—Quantity per inflorescence: Approximately 23. Arrangement: Imbricate in a single whorl. Aspect: Initially at acute angle to disc, becoming perpendicular at maturity. Shape: Oblanceolate. Margin: Entire. Apex: Emarginate with three tips. Base: Attenuate, fused to form a tube. Length: Approximately 3.8 cm. Width: Approximately 9.0 mm. Texture of upper surface: Glabrous. Texture of lower surface: Glabrous with a densely pubescent base. Color of upper surface when first open: N78B. Color of lower surface when first open: 76A with ribs of 77A. Color of upper surface when fully open: N78A with ribs of N79C. Color of lower surface when fully open: 77D with ribs of N79B.

Disc florets.—Quantity per inflorescence: Approximately 105. Arrangement: Massed in center of inflorescence. Shape: Tubular. Margin: Entire. Apex: Five

acute tips. Base: Attenuate, fused. Length: Approximately 7.0 mm. Diameter at apex: Approximately 2.0 mm. Diameter at base: Approximately 1.0 mm. Texture: Glabrous with a sparsely pubescent outer surface. Color when fully open: 79A at tips with center of N77C and base of 144D.

Disc.—Diameter: Approximately 1.5 cm. Depth: Approximately 5.0 mm.

Receptacle.—Shape: Conical. Height: Approximately 3.0 mm. Diameter: Approximately 4.0 mm. Color: 154D.

Phyllaries.—Quantity per inflorescence Approximately 17. Arrangement: In a single whorl. Shape: Linear to lanceolate. Margin: Entire. Apex: Acute. Base: Truncate. Length: Approximately 1.0 cm. Width: Approximately 2.0 mm. Texture of upper or inner surface: Densely pubescent at tip. Texture of lower or outer surface: Glandular pubescent. Gland color: Colorless. Color of upper or inner surface: 138B. Color of lower or outer surface: 138A.

Reproductive organs.—Androecium: Present on disc florets only. Stamen quantity: 5 per flower, fused around the style. Stamen length: Approximately 5.0 mm. Anther shape: Linear. Anther length: Approximately 2.0 mm. Anther color: N186B. Pollen amount: Abundant. Pollen color: 14B. Gynoecium: Present on ray and disc florets. Pistil quantity: 1 per floret. Pistil length: Approximately 7.0 mm. Stigma shape: Rounded. Stigma length: Less than 1 mm. Stigma color N92A. Style length: Approximately 5.0 mm. Style color: Colorless, transparent. Ovary length: Approximately 2.0 mm. Ovary color: 144D.

Seed and fruit production: Neither seed nor fruit production has been observed.

Disease and pest resistance: Resistance to pathogens and pests common to *Osteospermum* has not been observed.

What is claimed is:

1. A new and distinct cultivar of *Osteospermum* plant named 'Balserdarp', substantially as herein shown and described.
